UNITED STATES PATENT OFFICE

LEON BUEHLER, JR., OF WAYNESBORO, PENNSYLVANIA, ASSIGNOR TO FRICK COMPANY,
OF WAYNESBORO, PENNSYLVANIA, A CORPORATION OF PENNSYLVANIA

CAN FILLER

Application filed April 19, 1928. Serial No. 271,351.

My invention relates to can fillers, and more particularly to means for controlling or varying the capacity of the filler. The invention is designed primarily for use with 5 a can filler of the type forming the subject matter of my co-pending application, Serial Number 242,766, filed December 27, 1927.

A further object of the invention is to provide means for varying the capacity of the 10 can filler which will be more simple of operation and more readily manipulated than the volume changing means provided in known devices and in the application above referred to.

15 Referring to the accompanying drawing which is made a part hereof and on which similar reference characters indicate similar parts,

Figure 1 is a sectional view of a can filler, 20 showing my capacity varying means pivotally mounted therein,

Figure 2, a section on line 2--2, Figure 1,

Figure 3 is a partial section through the tank on line 3--3 of Figure 2.

25 In the drawing numeral 10 indicates the tank or can filler which is alternately filled and emptied for use especially for filling the ice cans in an ice making machine. The top of the filler has an air outlet 11, which is 30 closed by a float valve 12 when the water rises to fill the filler. A bucket 14 is pivotally mounted within the filler so that it may be tilted so as to allow a predetermined proportion of the capacity of the bucket to be retained in the bucket when the can 10 as a 35 whole is emptied. The bucket 14 is mounted upon a shaft 15 by means of straps 16 secured to the side of the bucket, which straps are secured on the shaft 15 by means of screws 40 or bolts 17, the said straps or brackets 16 having perforations 18 through which the shaft 15 passes. The straps also are bent over to form an L shaped hanging bracket, as shown.

45 A supporting bar 19 secured at 20 to the sides of the tank 10 provides a pivotal support for one end of the shaft 15. The other end of this shaft passes through a plate 21 which is secured within the tank 10 by means of bolts or rivets 22. The plate 21 has a screw threaded outer end upon which a cap 23 may be

screwed against a packing follower 24 for securing the packing 25 tightly around the shaft 15, to prevent leakage of fluid around this shaft. The outer end of the shaft 15 may be squared as shown at 26, to receive a 55 suitable handle for rotating the shaft.

The manner in which the device operates is as follows:

When in the position shown in full lines in Figure 1, with each filling and emptying of 60 the tank 10 the bucket 14 will displace a volume from the tank equal to its entire volume. When the bucket 14 is tilted so as to assume the position shown in dotted lines in Figure 1, only a portion of the total volume of the 65 bucket will remain filled with water, namely, the portion represented below the dotted line 27. When the bucket is in the last named position the can filler 10 supplies almost its whole volume in liquid to the ice can to be 70 filled. If desired of course the bucket 14 may be tilted until its contents will drain with each emptying of the tank 10. When in this position the filler 10 supplies its maximum volume to the cans which are filled. When the 75 bucket 14 is in the position shown in full lines the can filler 10 delivers its minimum quantity. Rotation of the shaft 15 will position the bucket 14 at any point intermediate the maximum volume and the minimum volume 80 of the filler 10, the shaft 15 being readily rotatable by means of a crank positioned on the squared end 26. The adjustment of the different volumes may be very quickly and easily 85 made.

While I have shown and described this invention for use with an ice making machine and particularly for filling the ice cans, it should be obvious that it should not be restricted to this use. It should be very apparent that it may find utility in varying the capacity of any tank or reservoir or can from which measured volumes of fluid are dispensed. The position of the bucket would indicate what part of the total volume of the can is displaced to leave the remaining volume as a resultant volume delivered to the receptacle which is filled.

It will be obvious to those skilled in the art that various changes may be made in my de- 100

vice without departing from the spirit of the invention, and I, therefore, do not limit myself to what is shown in the drawing and described in the specification, but only as set forth in the appended claim.

Having thus fully described my said invention, what I claim as new and desire to secure by Letters Patent is:

A filler for ice cans of a refrigerating system comprising a vessel having means therein movable to retain a predetermined volume of water, said means comprising a trough having ear portions secured to its ends, said ear portions having perforations to receive a shaft for supporting the trough, the ear portions being bent over and secured to the shaft to cause the trough to be rotated by the shaft, said shaft having one end journaled in a bracket in the vessel and having its other end extending out through the walls of the vessel by means of which shaft the trough is rotated to position it so as to retain a predetermined quantity of water in the vessel when the vessel is emptied whereby the effective volume of the vessel is controlled within predetermined limits, substantially as set forth.

In witness whereof, I have hereunto set my hand at Waynesboro, Pennsylvania, this thirteenth day of April, A. D. nineteen hundred and twenty-eight.
